HELMET

John Fisher, Dover, Del., assignor to ILC Industries, Inc.,
Dover, Del., a corporation of Delaware

Filed Mar. 29, 1968, Ser. No. 11,205

Term of patent 14 years

Int. Cl. D2—03

U.S. Cl. D2—233

FIG. 1

FIG. 3

FIG. 2

FIG. 1 is a front elevational view of a helmet showing my new design;

FIG. 2 is a side elevational view thereof;

FIG. 3 is a front elevational view thereof with the face shield positioned on the helmet above the face; and

FIG. 4 is a side elevational view thereof.

The face shield portion of the design has been shaded for transparency.

I claim:

The ornamental design for a helmet, as shown and described.
